(57) **CLAIM**

The ornamental design for automobile tire, as shown and
described.

DESCRIPTION

FIG. 1 is a front view of the automobile tire, showing the
new design, a rear view thereof, a top plan view thereof,
and a bottom plan view thereof appearing the same as the front
view;

FIG. 2 is a left side view of the automobile tire, a right side
view thereof appearing the same as the left side view;

FIG. 3 is a fragmentary front view, showing in enlargement,
the portion of 3—3 in FIG. 1; and,

FIG. 4 is a cross-sectional view in enlargement, taken on line
4—4 in FIG. 3.

In the drawing figures on the enclosed drawing, in which the
even broken lines represent environmental structure only
and form no part of the claimed design, the claimed design
being the tread pattern shown by solid lines, up to the
peripheral boundary between the tread and the sidewall of
the article, represented by dot-dash broken lines, which also
form no part of the claim.
